(57) **CLAIM**

The ornamental design for an electrical connector, as shown and described.

DESCRIPTION

FIG. 1 is a top, front, right side perspective view of a male terminal of an electrical connector, showing my new design; FIG. 2 is a bottom, rear, left side perspective view thereof; FIG. 3 is a front elevation view thereof; FIG. 4 is a rear elevation view thereof; FIG. 5 is a left side elevation view thereof; FIG. 6 is a right side view thereof; FIG. 7 is a top plan view thereof; FIG. 8 is a bottom plan view thereof; FIG. 9 is a top, front, right side perspective view thereof in an open state; FIG. 10 is a top, front, right side perspective view of a female terminal of the electrical connector; FIG. 11 is a bottom, rear, left side perspective view of the female terminal of the electrical connector; FIG. 12 is a front elevation view of the female terminal of the electrical connector; FIG. 13 is a rear elevation view of the female terminal of the electrical connector; FIG. 14 is a left side elevation view of the female terminal of the electrical connector; FIG. 15 is a right side view of the female terminal of the electrical connector; FIG. 16 is a top plan view of the female terminal of the electrical connector; FIG. 17 is a bottom plan view of the female terminal of the electrical connector; FIG. 18 is a bottom, rear, left side perspective view of the female terminal of the electrical connector in an open state; FIG. 19 is a top, front, right side perspective view of the electrical connector that shows the male terminal and the female terminal disconnected from each other; and, FIG. 20 is a top, front, right side perspective view of the electrical connector that shows the male terminal and the female terminal connected together.

(Continued)

The male terminal shown in FIGS. 1-9 and the female terminal shown in FIGS. 10-18 are shown separately for convenience of illustration.

The broken lines are included to show features that form no part of the claimed design.
